TOWEL VENDING CABINET

Joseph Darman, Utica, N. Y., assignor to Utica
Towel Cabinet Corp., Utica, N. Y., a corpora-
tion of New York

Refiled for abandoned application Serial No.
232,148, November 9, 1927. This application
January 24, 1934, Serial No. 708,144

2 Claims. (Cl. 194—75)

My invention relates to a towel vending cabinet, and I declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a machine adapted to hold a one piece towel of some considerable length that is wound from one removable roller to another upon which the soiled part is accumulated and then removed from the cabinet of the machine.

15 The passage of the towel from one roller to the other is controlled by certain mechanism hereinafter described adapted to allow the towel to be pulled in suitable lengths from a removable supply roller through an opening in the cabinet and thereafter wound upon a removable accumulating roller from whence it is taken in its soiled condition from the cabinet.

20 The mechanism for allowing the towel to be actuated thus is placed in operative condition by the insertion of a penny or other coin in a slot provided for the purpose.

25 The machine will be serviceable particularly in public places where the furnishing of a clean towel at a nominal price is desirable. Furthermore, it removes from the unscrupulous and souvenir gatherer the temptation to pilfer.

The object will be understood by referring to the drawings, in which:

30 Fig. 1 is a perspective view of the towel vending cabinet.

35 Fig. 2 is a vertical sectional view taken on the line 2—2 of Fig. 3 and looking in the direction toward the front of the machine, parts being broken away.

40 Fig. 3 is a vertical sectional view taken on the line 3—3 of Fig. 2 and looking in the direction of the arrows indicated, parts being broken away.

45 Fig. 4 is a vertical sectional view taken on the line 4—4 of Fig. 2 and looking in the direction of the arrows indicated.

50 Fig. 5 is a detail perspective view of a member employed for closing parts of the front of the machine.

Fig. 6 is a detail perspective view of a member employed for supporting the upper casing and immediate parts.

Fig. 7 is a detail perspective view of a base piece used for supporting the device.

55 Fig. 8 is a detail perspective view of certain connecting parts employed.

Fig. 9 is a detail perspective view of the disappearing cover employed.

Fig. 10 is a vertical sectional view taken on the line 10—10 of Fig. 2, parts being omitted.

Fig. 11 is a detail view showing a perspective 5 of the mechanism for actuating the towel, parts being broken away.

Fig. 12 is a detail perspective view of certain holding members employed.

Fig. 13 is a detail perspective view of an actuator 10 and immediate parts employed.

This application is a substitute for application filed November 9, 1927 Serial Number 232,148.

Referring more particularly to the drawings, the device embodies an upper casing 1 made preferably of metal and forming a cabinet adapted to house portions of the towel and mechanism for actuating the same. Casing 1 has hinged at 2, 2 a door 3 that is equipped with a mirror 4 and provided with a lock 5. Door 3 gives access to the upper part of the cabinet. A lower door 6 is hinged at 1, 1 and is provided with a lock 8. Door 6 gives access to the lower part of the cabinet. There is also a swinging shutter or disappearing member 10. 15

20 Member 10 embodies a curved surface 11 having its end portions bent at right angles and reduced in width to form arms 12, 12 which are fulcrumed to the inside surface of casing 1 at 13, 13. The means for actuating member 10 will be hereinafter described. 25

An intermediate or permanent partition 20 is disposed just in the rear of member 10. Partition 20 has formed therein two large apertures 21, 21 adapted to allow for observation therethrough to the interior of the cabinet. Partition 20 is held suspended in position by brackets 25, 25 that are attached by rivets thereto and at the other end bolted at 26, 26 to the inside of casing 1. Partition 20 has portions 28 and 29 30 extending in opposite directions thereto and formed at right angles to the body part 30, over which portions the towel 31 passes. 35

40 Casing 1 is fastened along its lower edge at several locations by bolts 35 to a casting or bottom part 36. Part 36 is provided with a ridge 40 having apertures 41 therein for the projection of bolts 35. A recess 42 is made in part 36 to accommodate certain parts hereinafter described. Ridge 40 is not continued across the 45 front, as at 43. A rectangular depending wall 45 is made integral with part 36 for the purpose of forming a channel 37 through the bottom surface of part 36. Wall 45 is reduced to 50 provide a shoulder at 47 against which the upper 55

edge of casing 48 rests. Casing 48 is somewhat extended and nearly rectangular in shape, its sides, however, converge slightly towards the top thereof.

5 The lower edge of casing 48 rests against a shoulder 50 formed in the reduced upper part of lateral walls 51 of floor piece 52. Walls 51 of floor piece 52 furnish a chamber for the reception of certain parts hereinafter described. A 10 recess 53 is made through walls 51 which are enlarged at 54, and extended inwardly at 55 for the projection of a pedal 56 having cross piece 57. The lower part of floor piece 52 tapers downward and has apertures 60 for the projection of 15 screws or bolts to fasten the piece 52 to the floor, not shown.

The mechanism for the actuation of disappearing member 10 from full to dotted line position shown particularly in Figs. 3 and 4, whereby to allow for exposure of towel 31 embodies links 65, 65 that are pivoted at 66 in each instance to the upper part and near the free ends of arms 12, 12 of member 10. The opposite ends of each of the links 65 are pivoted at 70 to a rock arm 71 fixed to turn with rod 72 rectangular in cross section and carried in side plates 73, 73 of auxiliary frame 74. The ends of rod 72 are rounded off to fit within the round apertures in plates 73, 73 that form the bearings. 25 The turning of rod 72 within a given arc of a circle will cause arms 71, 71 to exert a pull on links 65, 65 and hence effect the actuation of member 10 to dotted line position shown in Figs. 3 and 4 upon its fulcrums 13, 13. Member 10 30 will be returned automatically to its full line position, shown in Figs. 3, 4, 10 and 11 by coiled springs 75, 75 that are fastened in each instance at their lower ends to rock arms 76, 76 fixed to turn with rod 72. The upper ends of springs 75, 75 are fastened to one of the spacing bars 77 of auxiliary frame 74.

The means for rocking rod 72 in the first mentioned direction, whereby to move member 10 to open position contemplates a sector or mutilated gear 80 that is fixed to turn with one of the outer ends of rod 72. Gear 80 is disposed beyond the surface of lateral wall 73 of auxiliary frame 74 and within the wall of cover 81. A member 85 having a coin slot 80 is bolted to the lateral surface of gear 80 near its top edge. Member 85 is disposed at an angle downward, whereby the coin, in this instance a penny 88, will slide downward and lodge against vertically movable actuator 89 provided with a V-shaped recess 89—A 45 for receiving one edge of penny 88. The diametrically opposite edge of penny 88 will remain in slot 86, whereby to effect a rigid connecting link between gear 89 and actuator 89. The downward movement of actuator 89 will 50 rotate, therefore, gear 80 through a limited arc of a circle or until the penny is drawn into such position that it will fall by gravity free from the slot 86 in member 85 into removable cup 90, whereupon gear 80 will return to its 55 original position under the influence of the coiled springs 75, 75.

The means for holding member 10 in full line position, shown in Figs. 3 and 4, whereby to prevent unauthorized persons from reaching towel 31 unless a penny 88 is placed in slot 36, embodies releasing rock members 95 and 96. Each of members 95 and 96 is fixed to turn with a rock shaft 97 carried in bearings formed in side plates 73, 73 of auxiliary frame 74. Rock members 95 and 96 are disposed on the outside of plates 73,

however, and are equipped with ends 100 and 101 respectively that are formed at right angles thereto which project through enlarged openings 102, 102 made in plates 73, 73. Ends 100 and 101 are reduced, whereby to permit the lower edges 103, 104 of members 95 and 96 respectively to move below the lower edge of openings 102, 102. Ends 100 and 101 of members 95 and 96 respectively lie adjacent links 65, 65 which are formed with recesses 105, 105 for the purpose. The edges of 10 links 65, 65 at the location of recesses 105, 105 are made parallel to the surfaces of ends 100 and 101 of members 95 and 96, whereby to prevent any movement of said members 95 and 96 unless said ends 100 and 101 are first withdrawn from the 15 location of links 65, 65.

The means for actuating ends 100 and 101 towards engaging position with links 65, 65 embodies a beveled or tapered surface 110 formed on the free end 111 of member 96, beyond its fulcrum. The lower edge of tapered surface 110 rests upon shaft 115 projecting laterally from bracket 116 bolted to gear 80, whereby the turning of gear 80 in a counter clockwise direction will cause shaft 115 to impinge against the lower edge of tapered surface 110 and rock said members 95 and 96 in a counter clockwise direction to bring ends 100 and 101 opposite the edges of links 65, 65 at the location of recesses 105, 105, whereby to hold member 10 in closed position 30 illustrated in Figs. 3 and 4. When gear 80 is turned in the opposite direction or clockwise shaft 115 will move downward and, thereby, allow member 96 to rock back to original position under influence of coiled spring 129 which is attached at one end to the free end of member 95 and at the other to the projecting part of spacing rod 121 of auxiliary frame 73, whereby to exert a pull downward adapted to hold members 95 and 96 in locking or full line position illustrated in Figs. 3 and 4. Members 95 and 96 being 35 fixed to rock with shaft 97 will turn together.

When gear 80 turns in a clockwise direction to permit the actuation of members 95 and 96 to move ends 100 and 101 away from links 65, 65 it will at the same time rock rod 72 and thereby 45 actuate member 10 through the connections of links 65, 65 and arms 71, 71 to dotted line position shown in Figs. 3 and 4. Immediately gear 80 stops turning in clockwise direction it will tend to turn in the reverse direction under influence of coiled springs 75, 75 which are intermediately connected therewith through rod 72 as heretofore described. Gear 80 will be arrested in its return movement under influence of springs 75, 75 when the lower end of stop member 125 which is bolted at 126, 126 to gear 80, comes in contact with the upper end of adjustable upstanding rod 127. Rod 127 is carried in a bearing made in bracket 128 that is fastened to the outer surface of one 50 of the plates 73 of auxiliary frame 74. Nuts 130, 130 are mounted on rod 127 and disposed on opposite sides of the laterally projecting part of bracket 128, whereby to hold said rod 127 in given position. Stop member 125 can be moved off 55 from the upper end of rod 127 in a clockwise direction but will be unable to pass therebeyond when returning in a clockwise direction.

Actuator 89 is mounted to slide in a vertical plane upon spacing bracket 135 that is bolted at 70 136, 136 to one of the plates 73 of auxiliary frame 74, whereby said actuator is held a short distance from the surface of side plate 73. To this end elongated slots 138, 138 are made in actuator 89. Headed bolts 140, 140 that are screw mounted to 75

bracket 135 engage said slots 138, 138 whereby to hold said actuator 89 in sliding relation to bracket 135. A coiled spring 142 secured at one end to the horizontal part 143 of bracket 135 and at the other to screw bolt 144 mounted to actuator 80, tends to hold actuator yieldingly in uppermost position with bolts 140 resting against the lowermost edges of slots 138, 138.

Actuator 89 is drawn downward against the tension of spring 142 by means of a pedal 56 that has a foot piece 57 and is fulcrumed at 152 to the enlarged part 54 and extension 55 of walls 51 of floor piece 52. A link 155 is pivotally connected at one end to the free or inner end of pedal 56 and at the other to a bell crank lever 156 fulcrumed at 157 to shaft 158 carried in bearings 159, 159 made in part 36, which has a recess at 160 for the projecting of lever 156.

The other end of lever 156 is pivoted to a shaft 161 carried in bearings in the lower bifurcated enlarged ends of actuator 89. Pressure of the foot on cross piece 57 of pedal 56 will force link 155 upward and thereby rock lever 156 clockwise to draw actuator 89 downward against the tension of spring 142.

This motion of actuator 89 will be an idle motion unless a penny is lodged between member 35 and actuator 89 as above described. When said penny is lodged thus, gear 80 will turn on its central pivot with the results aforementioned and also revolve ratchet pinion 165 that is mounted on the side of spur gear 166 to turn upon a common pivot 167 projecting laterally from bracket 168 bolted at 169 to a plate 73 of auxiliary frame 74. A spring pressed pawl 170 pivotally mounted to the side of gear 166 is adapted to cause gear 166 and pinion 165 to turn together in a counter clockwise direction or during the initial turning of gear 80 when actuator 89 is moving downwards, whereby to turn idle gear 172 with which it meshes. Idle gear 172 is mounted to turn freely upon an arbor 173 mounted to project laterally from the side of plate 73. Idle gear 172 meshes with a pinion 174 fixed on the end of shaft 175 and adapted to turn with gear 176 also fixed to turn with shaft 175. Shaft 175 carries thereon and adapted to turn therewith, a roller 180 which is disposed between plates 73, 73 of auxiliary frame 74. Shaft 175 has loose bearings in plates 73, 73.

Roller 180 is in contact with roller 181 mounted on shaft 182 carried in bearings in plates 73, 73. A spur gear 185 is mounted on the end and adapted to turn with shaft 182. Gear 185 is in mesh with gear 176, whereby rollers 180 and 181 will turn in opposite directions to pull towel 60 therethrough. Towel 60 is wound in the first instance before placing in the cabinet on a removable roller 187 fixed to turn with shaft 188 carried in open L shaped bearings 189 made in plates 73, 73 of auxiliary frame 74. Towel 31 may be folded, however, and laid in the bottom part of the upper cabinet instead of being wound on a roller as 187. It is lead upward through the cabinet over a rod 190 carried in bearings in plates 73, 73 and thence between aforementioned rollers 180 and 181 and thence over rod 191 fixed at either end to bell arms 192, 192. Arms 192, 192 are pivoted at 193, 193 to plates 73 and are disposed on the outside thereof. Each of the arms 192 has a depending tooth or pawl 194 adapted to engage with the teeth of gears 185 and 195 fixed to the ends of shaft 182 and intended to turn therewith. Teeth 194, 194 are held normally just above and out of range with the teeth of gears 185 and 195 by

springs 196, 196 resting at their free ends in grooves made in the upper inner corners 197, 197 of arms 192, 192. The opposite ends of each of the springs 196 is fastened to a headed stud 198 mounted to project laterally from each of plates 73, 73.

Springs 196 are forced, in each instance, beneath pins 200, 200 projecting laterally from plates 73, 73 whereby to effect a tension on the free end, of each of said springs 196 adapted to hold teeth 194 of bell arms 192 off from engagement of the teeth of gears 185 and 195. The function of rod 190 which controls the action of teeth 194 on bell arms 192 is to limit the amount of towel than can be withdrawn from roller 187 each time the machine is operated by depositing a coin therein.

To this end towel 31 passes almost directly downward underneath the lower surface of partition 20 the edges of which are rounded for 20 the purpose, whereby a pull on towel 31 after the allowance has been made, will cause rod 191 to move downward and, thereby, permit teeth 194 to engage the teeth of gears 185 and 195 to arrest the further releasing of towel 31.

The end of towel 31 is passed upwards over the upper surface of partition 20 having rounded edges for the purpose and thence back underneath roller 20 mounted to turn with shaft 201 carried in bearings in plates 73, 73 of auxiliary 30 frame 74. One end of shaft 201 has mounted to turn therewith a pinion 202. Pinion 202 meshes with an idle gear 203 mounted to turn freely on a shaft 204 extending laterally from bracket 205 which is bolted at 206 to plate 73. A ratchet 35 pinion 207 is mounted also on shaft 204 adjacent gear 203. Spring pressed pawl 208 pivotally mounted to the side of gear 203 is adapted to cause pinion 207 to turn with gear 203 in one direction and to allow it to turn idle in the other. Pinion 40 207 is in mesh with sector or mutilated gear 80, whereby the turning of gear 80 will turn pinion 207 and also when turning in a counter clockwise direction gear 203, pinion 202 and roller 200a, whereby to cause towel 31 to wind upon removable roller 210, which is above roller 202 and is revolved by its contact with roller 200a. Roller 200a is allowed to turn only in one direction, whereby to prevent towel 31 from being pulled backward by ratchet pinion 211 fixed to turn 50 with shaft 201. Ratchet pinion 211 is engaged by pawl 212 pivoted at 213 to a plate 73 of auxiliary frame 74. Laterally projecting pin 214 prevents the free end of pawl 212 from moving out of range of the teeth of said ratchet pinion 211, 55 although sufficiently separated therefrom to allow pawl 212 to escape past the teeth of pinion 211 when turning clockwise.

Roller 210 is mounted on shaft 215 carried in open L shaped bearings 216, 216 formed in removable blocks 217 that are disposed between the upper edges of plates 73 and the top of casing 1.

In order to insure against the turning of roller 200a and the consequent take up turning motion of roller 210 when rollers 180 and 181 are revolved to release towel 31 sufficient for wiping and drying one's hands thereon, there is provided a detent 218 adapted to engage the teeth of gear 203 and remain in engagement therewith while rollers 180 and 181 are feeding towel 31 outwardly. Detent 218 is fulcrumed at 219 to rock member 220 which is pivoted on shaft 221 that projects laterally from a plate 73 of auxiliary frame 74. Detent 218 is held yieldingly in position by spring 222 that engages at one end the 75

top edge of detent 218 and at the other end engages a notch 223 made in the horizontally disposed end 224 of rock member 220. The middle part of spring 222 is wound about bolt 225 projecting laterally from the side of detent 218. Spring 222 will hold detent 218 yielding in given position illustrated in Fig. 13.

Detent 218 will be forced against the teeth of gear 203 when actuator 89 is moving downward, whereby to prevent the actuation of rollers 200a and 210 by the contact of roller bearing 226 against the beveled surface 227 of rock member 220. As actuator 89 moves downwardly roller bearing 226 will actuate rock member 220 into dotted line position illustrated in Fig. 13.

It will return to normal position illustrated in full lines in Fig. 13, whereby detent 218 will be free from the teeth of gear 203 under force of spring 230 that is wound about shaft 221 and has one end bearing against the front edge of rock member 220 and the other, on upper edge of a plate 73 of auxiliary frame 74.

Auxiliary frame 74 by which most of the above parts is supported is made adjustable with reference to part 36. To this end the lower sections of plates 73, 73 are bent at right angles as at 231, 231 to lay flat against the surface of part 36 and provided with elongated slots 232 for the projection of bolts 233 that hold said plates 73 to the upper surface of part 36.

An extension member 240 having a slot 241 for the passage of a coin as 88 is bolted to the side of upper casing 1. Member 240 is disposed in such manner that slot 241 thereof will be in prolongation of slot 85 of member 85, whereby said coin 88 will be permitted to pass thereto. Shield or depending stop member 245 is made integral with member 85. It is formed on the arc of a circle concentric with the perimeter of gear 80 and is adapted to arrest or stop the passage of coin 88 at the end of slot 241 in member 240 until the return of member 85 having slot 86 therein has moved back to original position. This function of stop member 245 will insure the passage of coin 88 to its final lodgment against actuator 89 even although the operator should drop a coin 88 in slot 241 before the operating parts have returned to their original positions.

The operation of the device is effected by first dropping a coin as 88 in slot 241 and then stepping on foot pedal 56. Coin 88 will pass through slots 241 and 86 to a position that will bridge the space between actuator 89 and member 85 which will move then downward causing gear 80 to turn therewith until coin 88 falls by gravity into box 90.

The turning of gear 80 will cause bracket 116 carrying shaft 115 to move away from under one end of member 96 which together with member 95 also on shaft 97 will rock ends 100 and 101 to move upward and away from the location of links 65, 65 whereby to permit the elevation of disappearing member 10 operated by gear 80 through its intermediate connections by way of rod 72, arms 71 and links 65, 65.

The elevation of member 10 will permit the operator to grasp towel 31 which will be fed outward to a limited degree by the turning of rollers 180 and 181. The turning of rollers 180 and 181 is effected by the turning of ratchet pinion 165, gear 166, idle gear 172, pinion 174 and spur gears 176 and 185 mounted to turn with rollers 180 and 181. In this downward movement of actuator 89, ratchet pinion 207 will turn idle so

as not to cause roller 200a to turn and take up the slackness of towel 31 as fed from between rollers 180 and 181. In the event the operator should attempt to secure more of towel 31 than is allowed by pulling thereon, rod 191 will be forced downward by the pull and thereby cause teeth 194 of arms 192 to engage the teeth of gears 185 and 195. This will prevent the further turning of rollers 180 and 181 and the escape of towel 31 therepast.

As soon as the operator releases foot pedal 56, actuator 89 will move upward under influence of spring 142 to its original position. Gear 80 will turn in the reverse direction under influence of springs 75, 75, intermediately connected therewith through arms 76, 78 and rod 72 upon release of towel 31. In this reverse motion of gear 80, ratchet pinion 165 will turn idle, so that rollers 180 and 181 will not turn and feed towel 31 outwardly. The return movement of gear 80 will cause the reverse turning of rod 72 which through arms 71, 71 and links 65, 65 will move member 10 to closing position illustrated in full lines Figs. 3 and 4. Simultaneously, gear 80 will cause the turning of ratchet pinion 207 and gear 203 which is fixed to turn with shaft 97 and thereby actuate members 95 and 96 to bring ends 100 and 101 respectively into locking position relative to links 65, 65.

The turning of gear 203 will turn also pinion 202 and, therefore, roller 203a, whereby to effect a turning of removable roller 210 upon which the soiled towel is accumulated. When towel 31 has been wound completely upon roller 210, door 3 can be opened and roller 210 removed. Likewise lower door 6 can be opened and a clean towel 31 wound upon a roller, as 187 inserted therein in place of the empty roller. Occasionally, cover 81 which is held in position by a depending lug 250 on the top portion fitting into a recess in the horizontal part 251 of casing 1 and by lug 252 of part 36 projecting through a complementary recess in the lower part of cover 81, can be removed by unlocking padlock 255 removably mounted to lug 252 through an aperture 256 therein and swinging the bottom portion of cover 82 outwardly and then elevating it to allow lug 250 to clear its recess in part 251 of casing 1. Cup 90 containing the pennies can be emptied and replaced and cover 81 again put in place and padlocked. Doors 3 and 6 will be closed and locked. The cabinet is ready then for further use.

Having thus described my invention what I claim as new and desire to secure by Letters Patent is as follows:

1. In a towel vending cabinet, means for exposing a towel, a gear for controlling the operation of said means, a coin chute on said gear to support a coin and a vertically movable member having means to engage a coin for actuating said gear, said chute being arranged to permit the coin to rest against the vertically movable member while supported in said chute in the path of the means on the said vertically movable member.

2. In a towel vending cabinet, means for exposing a towel, a gear for controlling the operation of said means, a coin chute on said gear to support a coin in horizontal position, and a vertically movable member having means to engage a coin for actuating said gear, said chute being arranged to permit the coin to rest against the vertically movable member while supported in said chute in the path of the means on the said vertically movable member.
